(57) **CLAIM**

The ornamental design for a smart heat press, as shown and described.

DESCRIPTION

FIG. 1 is a perspective view of a smart heat press showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a top perspective view of the smart heat press in an exploded configuration; and,

FIG. 10 is a partial enlarged view of portion 10 in FIG. 1. The uniform dash-dash broken lines depict portions of the smart heat press that form no part of the claimed design. The dash-dot-dash broken lines in FIGS. 1 and 10 are provided to define the enlargement field in each and form no part of the claimed design.
